UNITED STATES PATENT OFFICE

EDWARD J. BRANDT, OF WATERTOWN, WISCONSIN, ASSIGNOR TO BRANDT AUTOMATIC CASHIER COMPANY, OF WATERTOWN, WISCONSIN, A CORPORATION OF WISCONSIN

MONEY HANDLING MACHINE

Application filed February 12, 1930. Serial No. 427,833.

My invention relates to new and useful improvements in money handling machines and more particularly to a machine of this character wherein means are provided for supporting a plurality of stacks of coins, the coins of the several stacks being adapted for discharge or ejection by suitable mechanism operated through the manipulation of a key or keys by the person in charge of the machine.

The principal object of the present invention resides in the provision of a novel form of tray for supporting the stacks of coins, the tray being provided with a cover or front normally positioned to overlie the stacks of coins to prevent removal of the coins by unauthorized persons.

Another object of the invention consists in the provision of a tray of the above character in which a suitable lock is provided for normally locking the cover or front in position over the stacks of coins but adapted to be manipulated to release the cover or front whereby it may be moved to allow access to the coins in the tray or to allow for replenishing or supplying coins to the stacks.

A still further object of the invention resides in the provision of a tray of the character described adapted to be detachably connected to the machine and provided with means whereby the tray may be locked in position on the machine against unauthorized removal.

As a further object of the invention I provide means adapted to be carried by the tray, and manipulated by the operator of the machine, to be engaged with the lowermost coin or coins of each stack to prevent unauthorized withdrawal thereof or removal of the other coins in the stack thereabove, means also being provided and carried by the tray for operation to engage the coin ejecting mechanism or members to make the same inoperative so that coins will not be ejected or discharged from the stacks upon manipulation of the operating keys.

Still another object of the invention resides in the provision of a tray for supporting a plurality of stacks of coins and provided with a cover or front adapted to normally

be positioned over the stacks of coins, locking means being provided for normally locking the cover or front in position over the coins and for locking the tray in position on the machine, the locking means being operable in one direction for releasing the cover or front of the tray and in another direction to release the tray from the machine.

Another object of the invention consists in the provision of a tray of the character described for supporting stacks of coins provided with means adapted to be manipulated to engage the lowermost coin or coins of each stack to prevent unauthorized removal thereof and means for locking the first mentioned means in position engaging the coins.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:—

Fig. 1 is a side elevation of the machine with the coin supporting tray in position thereon.

Fig. 2 is a top plan view of the machine with the coin supporting tray in position thereon.

Fig. 3 is a fragmental section on the line 3—3 of Fig. 2 looking in the direction of the arrows.

Fig. 4 is a fragmental front view, partly in vertical section, of the machine with the coin supporting tray removed therefrom.

Fig. 5 is a rear face view of the coin supporting tray.

Fig. 6 is a front face of the coin supporting tray.

Fig. 7 is a horizontal section on the line 7—7 of Fig. 6 looking in the direction of the arrows.

Fig. 8 is a transverse vertical section on

the line 8—8 of Fig. 7 looking in the direction of the arrows.

Fig. 9 is a detail perspective showing the slidable bar, and operating mechanism therefor, for manipulating the ejecting members and members to engage the lowermost coins of the stacks.

Fig. 10 is a vertical section on the line 10—10 of Fig. 6 looking in the direction of the arrows.

Fig. 11 is a vertical section on the line 11—11 of Fig. 6 looking in the direction of the arrows.

Fig. 12 is a substantially horizontal section on the line 12—12 of Fig. 11.

Fig. 13 is a vertical section on the line 13—13 of Fig. 6 looking in the direction of the arrows.

Fig. 14 is a substantially horizontal section on the line 14—14 of Fig. 13.

Fig. 15 is a fragmental detail showing a portion of the tray front or cover in raised position.

Fig. 16 is a perspective showing a modified form of coin supporting tray.

Fig. 17 is an end view of the form tray shown in Fig. 16.

Fig. 18 is an end view of a still further modified form of coin supporting tray.

Fig. 19 is a transverse vertical section through the form of tray shown in Fig. 18 looking towards the end of the tray.

Fig. 20 is a transverse vertical section through the form of tray illustrated in Figs. 18 and 19 with the coin cover or tray front in raised position showing in elevation the inner face of the end of the tray or handle carrying the locking mechanism.

Fig. 21 is a fragmental detail with the plate of the lock shown in Fig. 20 removed to show the inner mechanism of the lock; and

Fig. 22 is a section on the line 22—22 of Fig. 21 looking in the direction of the arrows.

In the drawings 1 indicates the body portion of the machine, supported by the legs 2, and including the manipulating keys 3. At the forward or front end the body supports the coin receiving member or chute 4 having the discharge opening 5 normally closed by the slidable plate 6 shown more particularly in Fig. 3 of the drawings. When the slidable plate 6 is moved rearwardly the coins in the receiving member or chute 4 will be discharged through the opening 5 into the hand of the operator. When the keys 3 are manipulated they will operate suitable ejecting mechanism for ejecting or discharging coins from stacks supported in a tray to be later described and as the ejecting mechanism and operating means therefor may be of desired well-known form a detailed illustration thereof has not been made. However, for the purpose of illustration I have shown the ejecting mechanism as including a plate 7 adapted to be slid upon manipulation of a

suitable key or keys and this plate 7 has pivotally connected thereto an ejecting finger 8 adapted to normally be positioned to engage the edge of the lowermost coin or coins of a stack to eject the same upon operation of the slidable plate.

Pivotally connected to the finger 8 is a second finger 9 which normally engages the bottom of the coin supporting tray, to be later described, as shown more particularly in Fig. 3 of the drawings, the fingers 8 and 9 being urged in opposite directions by means of a coiled spring 10 surrounding a bolt 11 which extends through the fingers.

At the forward end the plate 7 is provided with a shoulder 12 adapted to be engaged by a roller 13 carried by the inner end of an arm 14 pivotally connected to the machine at 15.

The forward end of the arm 14 is provided with the downwardly extending vertical projection 16, to be engaged by a member, to be later described, carried by the tray for normally holding the roller 13 in raised position

out of engagement with the shoulder 12 of the slidable plate. A rod 17 is carried by the arm 14 and extends through the guide member 18, the rod being normally forced downwardly by means of the coiled spring 19.

While in the drawings I have illustrated but a single plate 7 with its associated mechanism it will be understood that the number of these plates, and associated mechanism, will correspond to the number of stacks of coins supported by the tray. For a further understanding of the ejecting mechanism, and operating means therefor, attention may be directed to my Patent No. 1,401,133, dated December 27, 1921. However, it will be understood that I do not limit myself to the specific formation of the ejecting mechanism or operating means therefor disclosed in this patent.

At the forward end the body of the machine is formed or provided with the supporting ledge or shoulder 20 for the coin tray and extending upwardly from this ledge or shoulder are the transversely spaced lugs or projections 21.

My improved form of tray, illustrated in Figs. 1 to 15, inclusive, is adapted to be removably supported on the shoulder or ledge 20 and consists of the back plate 22 and forwardly extending bottom flange 23 provided adjacent each end with an opening 24 through which the lugs or projections 21 on the ledge or shoulder 20 are adapted to pass as shown more particularly in Fig. 3 of the drawings.

As also shown more particularly in Fig. 3 the upper portion of the back plate 22 extends at an angle conforming to the angle or incline of the plate 25 at the front of the body 1 of the machine. Extending rearwardly from the back plate 22, adjacent the upper ends thereof, are the plates 26 which overlie the portion 27 of the body and are adapted to be engaged by the latch mem-

70

130

135

bers 28 as shown more particularly in Fig. 2 of the drawings. These latch members 28 are adapted to engage in notches 29 formed in the edges of the plates 26 and when so engaged prevent the upper edge of the tray from being swung outwardly with respect to the body of the machine. Extending forwardly from the back plate 22 are the vertically extending plates 30 forming the compartments 31, 32, 33, 34, 35, 36, 37 and 38 adapted to receive stacks of coins of various denominations. I have illustrated the compartments 31, 32 and 33 as adapted to receive stacks of "pennies", the compartment 34 to receive a stack of "nickels", the compartments 35 and 36 to receive stacks of "dimes", the compartment 37 to receive a stack of "quarters" and the compartment 38 to receive a stack of fifty cent pieces.

As shown more particularly in Fig. 6 of the drawings the lower ends of the plates 30 are received in recesses formed in the upper face of the bottom flange 23 of the tray. It will be understood that the lowermost coin of each stack will rest upon the upper face of the bottom flange 23 and formed in the upper face of the flange and extending transversely thereof are the recesses 39, these recesses 39 being so positioned that there will be a recess beneath each of the stacks of coins and they will be in alignment with the ejecting fingers 8. As shown more particularly in Fig. 3 of the drawings the fingers 8 and 9 extend into the recesses 39 and the end of the finger 8 is normally held in position to engage the edge of a coin or coins. Thus when the ejecting fingers are operated a coin or coins will be ejected from the stack for delivery into the receiving member or chute 4 and discharged through the opening 5 thereof when the slideable member or plate 6 is moved rearwardly. Formed in the bottom flange 23, and extending parallel with the recesses 39, are the recesses 40, there being a recess 40 adjacent each of the recesses 39 and positioned within one of the compartments receiving the stacks of coins. Pivotally mounted in each of the recesses 40 is a finger 41 having the rearwardly directed extension 42 and the forwardly directed angular portion 43 having the upwardly extending projection 44 at its forward end. The rear ends of these fingers 41 are normally held in raised position by means of the coiled springs 45 and the forward ends of the fingers are thereby held in lowered position, as shown more particularly in Fig. 8 of the drawings, and below the bottom surface of the lowermost coin in the stack so that the coins may be readily ejected. Formed in the rear face of the back plate 22 of the tray, and adjacent the lower edge thereof, is a longitudinally extending groove 46 which intersects the recesses 39 and 40 as shown more particularly in Fig. 5 of the drawings. Slid-

ably mounted in the groove 46 is a plate 47 having a plurality of longitudinally spaced recesses 48 formed along its bottom edge. At one side of each of the notches 48 is an inclined surface 49, a straight surface 50, and a projection 51 for a purpose which will be later described. The notches 48 will normally be positioned over the fingers 8 of the ejecting mechanism and the fingers 41 so that the fingers 8 will normally be positioned, as has been previously described, to engage the edge of a coin or coins and the extensions 42 of the fingers 41 will engage the inner surfaces of the notches as shown more particularly in Figs. 8 and 9 of the drawings. When the bar 47 is slid to the right of the position shown in Fig. 9 or to the left of the position shown in Fig. 5 the inclined surfaces 49 will first engage the top surfaces of the fingers 8 of the ejecting mechanism to lower the same and will then engage the upper edges of the extensions 42 of the fingers 41 and lower the same to in turn raise the opposite ends of the fingers to position the projections 44 to engage the edges of the lowermost coins in the stacks. With the projections 44 so positioned the lowermost coins in the stacks cannot be withdrawn from the several compartments and the free ends of the fingers 8 will be positioned below the lowermost coins in the stacks and will not engage the coins when the plates 7 are operated by the depression of the keys. In other words the ends of the fingers 8 will slide beneath the stacks of coins. In order to operate the bar 47 I provide the lever 52 pivotally connected to the end of the tray at 53 and normally held towards the front of the tray by means of the spring 54. The upper end of the lever is formed with the hook 55 while the lower end is formed with the substantially right angle extension 56 adapted to engage in a slot 57 formed in the head 58 of a shaft 59 which extends through the back plate 22 of the tray as shown more particularly in Figs. 10 and 11 of the drawings. As shown the head 58 will be positioned on the front face of the plate and secured to the shaft and positioned at the back of the plate is an arm 60 having a projection 61 operable in an elongated opening 62 formed adjacent one end of the bar 47. A finger engaging member 63 is formed on or secured to the lever 52 and extends in position to be readily engaged by a finger or thumb of the hand of the operator of the machine.

When the lever 54 is in the position shown more particularly in Figs. 9 and 10 of the drawings and bar 47 will be positioned as shown in Fig. 9 relative to the fingers 8 and fingers 41 as previously described with parts in position whereby coins may be readily ejected but when the finger engaging portion 63 is engaged and the lever pushed rearward-

ly the shaft 59 will be rotated to swing the arm 60 and slide the bar 47 to engage the inclined surfaces 49 with the fingers 8 and 41, as previously described, to lower the fingers 8 and make them inoperative to eject coins and to raise the projections 44 of the fingers 41 to engage the lowermost coins of the stacks to prevent withdrawal thereof. It can be appreciated that it will be desirable to 10 lock and hold the bar 47 in this last named position and for this purpose the hook 55 formed on the upper end of the lever 52 is adapted to engage the projection 64 formed on the slideable bolt 65 of the lock mechanism 15 disclosed more particularly in Figs. 10, 11 and 12 of the drawings. This slideable bolt is normally held in lowered position by means of the coiled spring 66 but is adapted to be raised when the shaft 67 having the key slot 68 is rotated, the shaft having a projection 69 operable in the fork 70 of the slideable bolt. When the lever is swung rearwardly the engagement of the hooked end thereof with the projection 64 will raise the slideable bolt 65 20 but the spring 66 will return the slideable bolt so that the projection 64 will hold the hooked end in its rearward position. When the lever is to be released a key is positioned in the key slot 68 and the shaft 67 rotated. The extension 69 will cause the slideable bolt 65 to be raised to release the projection 64 from the hook 65. When thus released the spring 54 will return the lever 52 and associated parts, including the bar 47, to their original positions. It will be understood that the bar 47 25 may be operated while the tray is positioned on the machine or when removed therefrom. Of course, when the tray is removed from the machine the movement of the bar 47 will have no action on the fingers 8 but will operate the fingers 41. Thus the lowermost coins of the stack may be held against removal either when the tray is positioned on the machine or removed therefrom.

30 In order to further prevent unauthorized removal of coins from the stacks I provide a cover or closure for the tray, this cover or closure consisting of the substantially vertically extending portion 71 extending over the front of the tray and the substantially horizontally extending portion 72 extending over the tops of the compartments and coins therein. The cover or closure is hinged at the top of the tray at 73 and those parts of the hinge carried by the cover or closure are provided with the projections 74 which engage the plates 75 forming the other parts of the hinge to properly hold the cover or closure in its raised position as shown in dotted lines more particularly in Fig. 3 of the drawings and in full lines in Fig. 15. The horizontal portion 72 of the cover or closure is provided with elongated openings 76, in number equal to the number of compartments receiving the stacks of coins. These

35 elongated slots or openings are used for inserting or dropping the coins into the several compartments when the cover or closure is locked in closing position in a manner to be later described. The vertical portion 71 is 40 provided with vertically spaced rows of elongated openings 77 which are used as sight openings for observing the condition of the stacks of coins. In other words there is a line of elongated openings in front of each 45 of the compartments and stacks of coins therein and the operator by looking through the openings they see whether it is necessary to replenish the stacks. As previously stated 50 I provide means for locking the cover or closure in lowered position and this locking means includes a hooked projection 78 carried by the cover or closure at one end and adapted to engage a projection 79 on a slideable bolt 80 operable in a recess 81 at the end 55 of the tray opposite to that having the means for operating the bar 47. This slideable bolt 80 is normally held in raised or locking position by means of the coiled spring 82 shown 60 more particularly in Fig. 13 of the drawings. For releasing the slideable bolt from the hooked projection 78 I provide the shaft 83 having the projections 84 and 85 on its inner end. When the shaft 83 is rotated in 65 one direction the projection 84 will engage the arm 86 of the slideable bolt to lower the slideable bolt and release the projection 79 from the hook 78. When thus released the cover or closure may be swung upwardly. The shaft 83 is provided with the key opening 87, as shown more particularly in Fig. 1 of the drawings, to receive the key for 70 rotating the shaft. I also provide means whereby the entire tray may be locked on the front of the body of the machine. For this purpose projections 88 and 89 are secured to the front plate 25 of the body and extend forwardly therefrom to be received in the recesses 90 and 91, respectively, formed in 75 the back plate of the tray. The projection 89 is formed with a hook 92, as shown more particularly in Fig. 13, and this hook is adapted to engage the projection 93 carried by the slideable bolt 94 operable adjacent to 80 and in the same recess 81 with the slideable bolt 80. This slideable bolt 94 is normally held in raised position by means of the coiled spring 95. When it is desired to unlock and 85 remove the tray from the machine the shaft 83 is rotated in a direction opposite to that in which it is rotated for operating the slideable bolt 80 and when thus rotated the projection 85 will engage the arm 96 formed on the slideable bolt to lower the bolt and release the projection 93 from the hook 92. When 90 thus released the tray may be removed from the machine after releasing the latches 28 previously described. It will thus be seen that the slideable bolts 80 and 94 are operable 95

100

105

110

115

120

125

130

through means of the same shaft which is rotated by a single key.

The ends of the tray are formed by the handles or hand holds 97 and 98, the handle or hand hold 97 carrying the locking mechanism for the sliding bar 47 whereas the handle or hand hold 98 carries the locking mechanism for the cover or closure and for locking the tray to the machine.

10 As shown more particularly in Figs. 2 and 6 of the drawings the vertically extending portion 71 of the cover or closure is of irregular configuration so as to provide the enlarged or swelled portions for the coins of 15 larger diameter and it will be understood that the handles or hand holds 97 and 98 will be engaged to remove the tray bodily from the machine or to replace the same thereon.

15 Swinging members 99 are carried by the back plate 22 of the tray and operate in openings 100 formed therein. There is one of these swinging members for each of the compartments of the tray and as shown more particularly in Fig. 3 of the drawings the 20 forward edges of the members are adapted to be engaged by the coins in the stacks to force the members rearwardly. Each of the members is provided with an extension 101 adapted to engage the depending portion 16 of an arm 14 and to normally hold the opposite end of the arm in raised position. When the coins in the stacks get so low that they do not engage the swinging members the members will swing inwardly and the 25 arms 14 will lower so that the rollers 13 will engage the shoulders 12 of the members or plate 7 and prevent operation thereof. This gives notice that the coins in the stacks must be replenished. The arm 14 is normally urged towards lowered position by means of 30 the coiled spring 19.

35 From the above detail description it will be seen that in Figs. 1 to 15 inclusive of the drawings I have illustrated a novel form of coin supporting tray adapted to be readily attached to or removed from the body of the machine and means are provided for locking the tray to the machine against removal by an unauthorized person. At the same 40 time I have provided a cover or closure for the tray so that access may not be had to the coins by an unauthorized person and have further provided a lock for the cover or closure. Means are also provided for preventing removal of the lowermost coins from 45 the stacks and for making the ejecting fingers inoperative. But a single key is necessary for unlocking the tray from the machine and for unlocking the cover or closure for the 50 tray. With a construction such as I have disclosed and described it is not necessary for the attendant to remain constantly at the machine for with the tray locked to the machine, the cover or closure locked over the tray, and 55 the mechanism operated to hold the lower-

most coins against withdrawal and the ejecting inoperative no unauthorized person could possibly remove the coins. It will be understood that where more than one coin is to be ejected from a stack upon each operation of the ejecting mechanism that the members that engage and prevent removal of the lowermost coins will engage that number of coins that are usually adapted to be ejected.

60 In Figs. 16 and 17 of the drawings I have illustrated a modified form of the invention in which the coin supporting tray is provided with a cover or closure and in which there are no locks for the cover or front, no lock for locking the tray to the machine proper, and no means for making the ejecting mechanism inoperative to discharge coins from the stacks or to engage the lowermost coins of the stacks to prevent unauthorized withdrawal thereof. In this form of the invention the tray for supporting the coins is indicated generally at 102 and is provided with the usual compartments or magazines for receiving the stacks of coins. The cover or closure is shown at 103 and is hingedly connected to the tray at 104. The cover or closure is provided in its vertically extending portion with the openings 105 through which the operator may observe the condition of the stacks of coins to ascertain when it is necessary to replenish. At the ends the tray is provided with the handles or hand grips 106 whereby the tray may be readily carried and positioned upon the machine or removed therefrom. An opening 107 is provided adjacent each end of the bottom of the tray to receive the projections 21 carried by the body of the machine and which position the bottom of the tray relative to the body of the machine. In this modified form of the invention plates 108 are provided on the tray, corresponding to the plates 26 illustrated in the preferred embodiment of the invention, and adapted to be engaged by the latch members 28. It will be understood that 100 in this modified form of the invention the cover or closure may be raised and lowered without manipulating any locks whatsoever, whereby access may be gained to the coin supporting compartments or magazines and 105 the stacks of coins themselves.

110 In Figs. 18 to 22 inclusive I have illustrated another modified form of my invention in which a lock is provided for the cover or closure of the tray but in which no lock is provided for locking the tray to the machine and no means are provided for making the ejecting mechanism inoperative for ejecting coins nor engaging the lowermost coins of the stacks for preventing unauthorized discharge thereof. The modified form of the invention disclosed in Figs. 18 to 22 inclusive is 115 the same as that disclosed in Figs. 16 and 17 except that a lock is provided for the cover or closure. In this modified form the tray is 120 125 130

indicated generally at 109 and the cover at 110, the cover or closure being hingedly connected to the tray at 111. Handles or hand grips 112 are provided at the ends of the tray 5 and the handle or hand grip at the right hand end thereof carries a key operated lock indicated generally at 113 and including a pivoted dog or bolt 114 having the extension 115 adapted to be received in an opening 116 10 formed in one end of the cover or closure, as illustrated more particularly in Figs. 19 and 22 of the drawings. The lock further includes a slidable member 117 operated through means of the rotatable barrel 118 15 which may be rotated by means of a key inserted in the slot 119. The slidable member 117 carries a plate 120 which engages the beveled end 121 of the dog or bolt 114. The extension 115 of the dog or bolt will normally 20 engage in the opening 116 of the cover or closure and lock the same in closed position. When the member 117 is slid inwardly by manipulation of the barrel 118 by the key the plate 120 will ride over the inclined end 25 of the dog or bolt 114 and cause the same to swing to release the projection 115 from the opening 116. When the lock is released the cover or closure may be raised as shown more particularly in Fig. 20 of the drawings. 30 When the cover or closure is lowered the end thereof will ride over the beveled or inclined end 121 of the dog or bolt 114 and cause the same to give sufficiently to allow the projection 115 to snap into the opening 116. 35 Having fully described my invention what I claim as new and desire to secure by Letters Patent is:

1. In combination with a money handling machine, a coin supporting tray adapted to be 40 readily positioned relative to the machine or removed therefrom, a cover carried by the tray and normally positioned to prevent access to the coins, and means for locking the cover in its normal position and for locking 45 the tray to the machine, said means being operable in one direction for releasing the cover and in another direction for releasing the tray from the machine.
2. In combination with a money handling 50 machine, a coin supporting tray adapted to be readily positioned relative to the machine or removed therefrom, a cover carried by the tray and normally positioned to prevent access to the coins, and single key operated 55 means adapted for locking the cover in its normal position and for locking the tray to the machine, said single key operating means being operable in one direction for releasing the cover and in the opposite direction for 60 releasing the tray from the machine.
3. In combination with a money handling 65 machine having coin ejecting means, a tray for supporting a stack of coins in position to be engaged by the ejecting means, said tray being readily removable from the ma-

chine, a finger normally positioned relative to the stack of coins to permit ejection of the lowermost coin, and means carried by the tray and adapted to engage the finger with the lowermost coin of the stack to prevent removal thereof while the tray is positioned upon the machine or removed therefrom.

4. In combination with a money handling machine having coin ejecting means, a tray 75 for supporting a stack of coins in position to be engaged by the ejecting means, said tray being readily removable from the machine, a finger normally positioned relative to the stack of coins to permit ejection of the lowermost coin, and common means adapted to be engaged with the ejecting means to make the same inoperative while the tray is positioned upon the machine and with the finger to engage the same with the lowermost 80 coin of the stack to prevent removal thereof while the tray is upon the machine or removed therefrom.

5. A tray for supporting a stack of coins including a pivoted finger normally positioned to permit removal of the lowermost 90 coin from the stack, and means for operating the finger to position the same to prevent removal of the coin.

6. In a tray for supporting a stack of 95 coins, a pivoted finger carried thereby, means for normally positioning the finger to allow removal of the lowermost coin from the stack, and means carried by the tray adapted to be operated and engaged with the finger to position the same to prevent removal of the lowermost coin from the stack.

7. In a tray for supporting a stack of coins, a pivoted finger carried thereby, means for normally positioning the finger to allow removal of the lowermost coin from the stack, and a bar slidably mounted on the tray and adapted to be engaged with the finger to position the same to prevent removal of the lowermost coin from the stack.

8. In a tray for supporting a stack of coins, a pivoted finger carried thereby, means for normally positioning the finger to allow removal of the lowermost coin from the stack, and a bar slidably mounted on the tray, said bar having inclined surfaces adapted to engage and operate the finger to position the same to prevent removal of the lowermost coin from the stack.

9. In combination with a money handling machine having coin ejecting means, a readily removable tray for supporting a stack of coins in position to be engaged by the ejecting means, a finger carried by the tray and normally positioned to allow ejection of the lowermost coin from the stack, and means carried by the tray and slidable relative to the ejecting means and finger for making the ejecting means inoperative and to posi- 120

tion the finger to prevent removal of the lowermost coin from the stack.

10. A coin tray for supporting a stack of coins including a finger pivotally connected to the tray and adapted to be normally positioned to permit ejection of the lowermost coin from the stack, a member carried by and slidable relative to the tray and engaging the finger to position the same to prevent

removal of the lowermost coin from the stack, means for operating said member, and means engageable with said operating means for holding the slidable member in engagement with the finger.

15. In testimony whereof I hereunto affix my signature.

· EDWARD J. BRANDT.
